UNITED STATES PATENT OFFICE.

FRANK H. BOLTE, OF MILWAUKEE, WISCONSIN, ASSIGNOR TO THE EGEL-HOFF MANUFACTURING COMPANY, OF SAME PLACE.

HORSE HAY-FORK.

SPECIFICATION forming part of Letters Patent No. 309,022, dated December 9, 1884.

Application filed May 16, 1884. (No model.)

To all whom it may concern:

Be it known that I, FRANK H. BOLTE, of Milwaukee, in the county of Milwaukee, and in the State of Wisconsin, have invented certain new and useful Improvements in Hay-Forks; and I do hereby declare that the following is a full, clear, and exact description thereof.

My invention relates to improvements in hay-forks, and will be fully described herein-after.

In the drawings, Figure 1 is a front elevation of my improved device in position when loaded. Fig. 2 is an enlarged side view, partly in section, showing the position of the locking device when the fork is loaded and hoisted. Fig. 3 is a like view showing said locking device when in position for loading.

The object of my invention is to provide means whereby a hay-fork will be adapted to pile the hay higher in the loft than it has heretofore been possible on account of the great height of the fork-head, caused by the form of the parts used to lock the fork in its various positions. The locking device I have designed for my fork very materially reduces the height of the fork-head, and will thus allow the load to be raised nearer the ceiling of the loft or the roof of the barn, and to consequently decrease the hand-labor which has to be resorted to in order to fill the space.

The bars A A' form the head of the fork, the part A' of which is connected to the upper end of the hollow legs B B, while the part A is connected to the upper end of the sliding rods C C, which latter have vertical play within the tubular legs B B, and have bifurcated lower ends, carrying the retaining-tines D D.

In the center of the part A' of the fork-head, and integral with or fastened to the same in any suitable manner, is a bifurcated arm, a, projecting vertically downward, and in the lower end of this arm is pivoted the U-shaped lever E, the short arm e of which has an outer lug, e', slightly enlarged on its outer end and perforated to receive the actuating-cord e'', attached thereto. Projecting on the inner edge of said arm e and at right angles to it is the locking-latch e''. The upper inner edge of this

latch is rounded, so as to enable it to slip from under the part A when this latter is pushed down to extend the retaining-tines D into the hay.

A notch, a', is cut in the inner rim of the hoisting-ring of the bar A, to receive the latch e'', which locks the fork in position for hoisting. The long arm e of the lever E is also provided with a lug projecting outward from it. This lug is notched inward to form the locking stop or shoulder e''. The function of this shoulder is to hold the cross-bars of the head of the fork apart, with the tines D retracted—that is, in position for penetrating the hay—the shoulder being then held by the under side of the bar A, as shown in Fig. 3.

The relation of the tines, their supporting-rods, and the connecting-links, as well as their method of attachment and operation, forms no essential feature of my present invention, but, as shown, is substantially the same as in my patent for a single hay-fork, granted me August 21, 1883, No. 283,694.

Having thus described my invention, what I claim as new, and desire to secure by Letters Patent, is—

1. In a double hay-fork, a locking-lever pivoted to one of the cross-bars of the head of the fork, hollow legs B B, and sliding rods C C, with a lever pivotally attached to the bar A', and having arm e, with locking-latch e'', whereby it is adapted to lock the fork in position for loading or hoisting, substantially as set forth.

2. In a double hay-fork, the combination of the cross-bars A and A', forming the head of the fork, hollow legs B B, and sliding rods C C, with a lever pivotally attached to the bar A', and having arm e, with locking-latch e'', whereby both of the cross-bars are adapted to be locked close together, with the locking-latch in a vertical line with the pivot of the lever when the fork is in position for hoisting, substantially as and for the purpose set forth.

3. In a double hay-fork, the combination of the cross bars A and A', hollow legs B B, and sliding rods C C, with a lever pivotally attached to the bar A', and having an arm, e'', with stop or locking-shoulder e'', whereby the cross-bars are adapted to be locked at the farthest distance apart when the fork is in posi-

tion for loading, substantially as and for the purpose set forth.

4. In a double hay-fork, in combination with the cross-bar A, having a notch, a', and the cross-bar A', having the arm a, the lever E, pivoted to said arm and having lug e' for actuating-cord e², and locking-latch e³ and the stop e⁴, substantially as shown and described, and for the purpose set forth.

In testimony that I claim the foregoing I do have hereunto set my hand, at Milwaukee, in the county of Milwaukee and State of Wisconsin, in the presence of two witnesses.

FRANK H. BOLTE.
